VENDING MACHINE

Myron H. Richardson, Chicago, Ill., assignor to
 Advance Machine Company, Chicago, Ill., a
 Corporation of Illinois

Application March 19, 1930. Serial No. 437,210

12 Claims. (Cl. 312—67)

This invention relates to improvements in vending machine of the type in which there is maintained a plurality of supplies of articles, one preferably arranged in advance of the other, the articles being completely delivered or dispensed from one of the supplies, after which the articles will be delivered from the other supply.

A further object is to provide an improved machine of this character having a single delivery station adjacent which one of the supplies is arranged, and improved means embodying a container or holder for the other supply which is adapted to be shifted automatically to a position adjacent the delivery outlet in the absence of any articles in the first supply.

A further object is to provide in a machine of this character a single ejector mechanism for both of the supplies, and improved means whereby the ejector will under certain conditions shift the second supply or holder into a position that the articles from said second supply may be delivered by the said ejector through the delivery opening to the operator of the machine. To the attainment of these ends and the accomplishment of other new and useful objects as will appear, the invention consists in the features of novelty in substantially the construction, combination and arrangement of the several parts, hereinafter more fully described and claimed and shown in the accompanying drawings illustrating this invention, and in which

Figure 1 is a rear elevation of a machine of this character constructed in accordance with the principles of this invention and with the back of the casing removed.

Figure 2 is a front elevation of the machine.

Figure 3 is a detail perspective view of the containers or holders for the articles to be vended.

Figure 4 is a detail sectional view taken on line 4—4, Figure 1, with parts omitted, and showing the shiftable container in one position.

Figure 5 is a view similar to Figure 4, showing the shiftable container in another position.

Figure 6 is a detail sectional view taken on line 6—6, Figure 7, with parts omitted.

Figure 7 is a sectional view taken on line 7—7, Figure 6, with parts omitted.

Figure 8 is a detail sectional view of the coin operating mechanism.

Figure 9 is a view similar to Figure 6, showing the parts in their normal positions.

Figure 10 is a view similar to Figure 9, showing the parts in another position.

Figure 11 is a perspective view of a detail.

Figure 12 is a detail perspective view of the member for shifting the movable container.

Referring more particularly to the drawings the numeral 15 designates an enclosing casing which may be of any desired size and configuration and is provided with a delivery or discharge outlet 16 in the front thereof, through which the articles to be vended are delivered. The front 17 of the casing is provided with a window 18 through which the articles to be vended may be viewed, and arranged also at the front of the machine is an operating handle 19 of a coin controlled device.

Arranged within the casing 15 is a supplemental casing 20 which may be secured in position in any suitable manner, adapting the same for bodily movement from the casing 15 when desired.

Within the casing 20 is arranged a container 21 for containing articles 22 to be vended. This container 21 is pivotally connected by one end as at 23 to the walls of the casing 20, and the bottom of the container 21 is open so as to allow the articles held therein to be discharged therefrom.

The container 21 is arranged within the casing 20 so that it will be spaced from the wall 24 thereof to form another space 25 so as to form with the wall of the casing a second container for holding a supply 26 of articles to be vended. The container 21 is so arranged with respect to the supply 26 that it will be in the rear thereof and so that the delivery opening of the container 21 will be spaced from the delivery station in the machine.

Mounted within the casing 15 is a slide 27, preferably in the form of a hollow frame as shown more clearly in Figure 6, and carried by the frame is an ejector element 28. The frame 27 and ejector 28 are movable over a support 29, the latter being arranged below the outlet of the container 25 so that the articles 26 will be delivered upon the support or platform 29 when the ejector 28 is moved from the position shown in full lines in Figure 10 to the position shown in dotted lines.

The ejector is adapted to be reciprocated in any suitable manner preferably by means of coin controlled mechanism designated generally by the reference numeral 30 in Figure 8.

Any suitable coin controlled mechanism may be employed for this purpose. Suffice it to say that the coin controlled mechanism embodies a coin carrying disc 31 having a coin pocket or seat 32 therein, from which the coin is adapted

to be delivered by the operation of a shaft 33 to which is connected the operating handle 19. The coin is normally held against delivery from the seat 33 by means of a spring controlled finger 34 which is movable adjacent the periphery of the coin to hold it in its seat, well known in this art.

A cam 35 is controlled by the coin controlled mechanism and the rotation of this cam will cause it to engage projections 36-37 on a pivotally mounted lever arm 38. The lever 38 is preferably bifurcated to form arms 39 which engage over projections 40 on the slide 27, also in a manner well known in this art, so that when the proper coin is inserted and when the spring finger 34 is removed, the cam 35 will be operated to rock the lever 38 and thereby reciprocate the slide 27.

Connected with the finger 34 is an arm 41 which in turn is connected with the rock shaft 42 and the end of the shaft is shaped to form an arm 43 adapted to project upwardly through a space 44 in the support or platform 29 to be engaged by the articles as they are delivered from the container to the platform 29 to depress the arm 43, rock the shaft 42 and withdraw the spring finger 34 so as to permit the coin to be deposited into the machine. This releasing mechanism is also of the ordinary and well known construction and constitutes no part of the present invention.

Mounted upon a suitable support preferably one of the walls of the casing 15, is a slide 45 which is provided with a lateral projection 46 at one end thereof. Connected with the other end of the slide 45 as at 47 is an arm 48 which is pivotally mounted as at 49 in a fixed bearing 50. The other end 51 of the arm is preferably slightly yielding and extends downwardly and in a position to engage a lateral face of the articles as they are delivered from the container 25, and the normal tendency of the articles 26 in the container 25 is to move the arm 48 in a direction to hold the slide 45 substantially at the limit of its movement in one direction.

Pivotaly mounted upon the slide 27, preferably at the rear thereof, is a rock shaft 52 journaled in suitable bearings. One end of the shaft is shaped to form a catch 53 that projects to the rear of the slide. The other end of the shaft is shaped to form a depending arm or finger 54, a spring 55 being provided which tends normally to elevate the hook 53, a stop 56 being also provided to limit the movement of the catch 53 under the influence of the spring 55.

The arm 54 is arranged in the path of movement of the lateral projection 46 on the slide 45, as shown more clearly in Figures 9 and 10, so that when the slide 45 is moved forwardly from the positions shown in Figure 6 to the positions shown in Figures 9 and 10, by the pressure of the article from either of the containers against the arm 51, the catch 53 will be held depressed but, in the absence of any articles exerting pressure against the arm 51, as shown in Figure 6, the slide 45 will be held against forward movement and the spring 55 will elevate the catch 53 to the position shown in Figure 6.

As the slide 27 and ejector 28 are moved to the rear from the position shown in Figures 9 and 10, to the position shown in Figure 6, that is when there is no article pressing against the arm 51 to hold the catch 53 depressed, the arm 54 engaging the projection 46 on the slide 45 will

move the slide 45 backwardly or to the position shown in Figure 6, to swing the arm 51 to the position shown in this figure.

Pivotaly mounted upon a suitable support such as a shaft 57 and at the rear of the container 21, is a member 58 preferably provided with upwardly projecting fingers 59 that are adapted to be moved into engagement with the back of the container 21. The member 58 is provided with a forwardly projecting portion 60 preferably intermediate the fingers 59 and such portion is provided with an opening 61 to form a shoulder 62 so positioned that the catch 53 will engage the shoulder 62 and the catch will be adapted to pass into or through the opening 61.

When the catch 53 is elevated, which will be at a time when there are no articles pressing against the arm 51, and the slide 27 with the ejector 28 is moved rearwardly or from the dotted line position shown in Figure 10 to the full line position shown in Figures 10 and 6, the catch will enter the opening 61 in the portion 60 of the member 58 so that upon the forward movement of the slide 27 and ejector 28 from the full line to the dotted line position shown in Figure 10, the member 58 will be swung about its pivot on the shaft 57 to cause the fingers 59 to move into engagement with the back of the container 21 and to shift the latter from the position shown in Figure 9 to the position shown in Figures 6 and 10, during the forward movement of the ejector, thereby positioning the articles 22 in the container 23 to be delivered therefrom and into a position to be ejected by the ejector 28 upon subsequent operations of the latter. In other words, when the container 25 is empty the absence of articles in such container will cause the member 58 to be automatically connected with the ejector so that upon operation of the ejector the container 21 will be shifted so that the articles can be delivered therefrom.

After the container 21 is empty it is necessary to reset the same manually from the position shown in Figure 10, back to the position shown in Figure 9.

As soon as any of the articles from the container 21 contact with the arm 51 the catch 53 will be rendered inactive and the member 58 will be disconnected from the ejector so that in the subsequent operations of the ejector the member 58 will not be affected.

The container 21 is locked in its normal and also in its adjusted position in any suitable manner. A simple and efficient means embodies a rock shaft 63 (see particularly Figures 4 and 5) journaled in suitable bearings 64. The ends of the rock shaft are shaped to form depending catches 65 (see also Figures 6, 9 and 10) that are adapted to enter openings 66 in laterally projecting members 67 when the container is moved into the position shown in Figures 5 and 6 and to engage behind one edge 68 of said members 67 when the container 21 is in the position shown in Figures 4 and 9.

A spring 69 tends normally to move the catches 65 into operative positions.

The shaft 63 between the catches 65 is shaped to form a crank as shown more clearly in Figures 6, 9 and 10, which is so disposed that when the parts are in the position shown in Figure 9, the crank will be in proximity to a portion of the member 58 or fingers 59 thereof.

When in this position (as shown in Figure 9) and the catch 53 is rendered active so as to permit it to engage the shoulder 62 on the portion 60 of the member 58 in a manner as already described, upon a subsequent operation of the 5 ejector the member 58 or fingers 59 will engage the crank portion of the shaft 63 and rock the latter in its bearings, thereby releasing the catches 65 from behind the edge 68 of the member 67, thereby adapting the container 21 for 10 movement about its pivot 23 by the pressure of the fingers 59 against the back of the container until the container reaches the position shown in Figure 10, at which time the catches 65 will be in positions to drop into the openings 66 in the members 67, thereby locking the container 21 against retrograde movement.

After the supply in the container 21 has been exhausted and it is desired to reset the mechanism, it will be necessary to move the slide 27 20 and ejector 28 rearwardly so as to move the member 58 and fingers 59 into the position shown in Figures 9 and 10. This can be accomplished by inserting a coin in the coin controlled 25 mechanism. The crank shaft 63 may then be rocked manually to release the catches 65, after which the container 21 may be swung backwardly upon its pivot to the position shown in Figure 9.

It is thought that the operation of this mechanism will be clearly understood from the foregoing, but briefly stated, it is as follows. When both of the containers 21 and 25 are filled with 30 articles and the parts are in the position shown in Figure 9, the mechanism will be in its normal position.

The articles 26 from the container 25 are successively discharged by the operation of the ejector 28 and slide 27, the presence of articles in 40 the container 25 holding the catch 53 inactive with respect to the member 58, by reason of the fact that the slide 45 will be held forwardly by the pressure of the articles 26 against the arm 48 so that the projection 46 engaging the arm 45 will hold the catch 53 depressed so that during 45 the reciprocation of the slide and ejector, while the articles 26 are being delivered from the container 25, the catch 53 will reciprocate through the opening 61 of the member 58 and will not 50 engage the shoulder 62.

When, however, the supply 26 is exhausted, the slide 45 will be moved rearwardly by the arm 54 engaging the projection 46 on the slide to shift the arm 51 which controls the slide 45, to the 55 position shown in Figure 6. This will also cause the projection 46 to move away from the arm 54 of the catch 53 and the spring 55 will raise the catch so that upon the next forward movement of the slide 27 and ejector 28, the catch 53 will 60 engage the shoulder 62 on the member 58 and rock the latter about its pivot 57.

The rocking of the member 58 will cause it to rock the shaft 63 to release the catches 66 from 65 engagement with the edge 68 of the members 67. A continued movement of the slide 27 and ejector 28 in the same direction will correspondingly move the member 58 into engagement with the back 23 of the container 21 to shift the latter 70 into the positions shown in Figures 10 and 6.

The articles 22 in the container 21 will then engage the arm 51 to shift it and thereby cause the projection 46 on the slide 45 to engage the arm 54 to depress the catch 53 and thereby disconnect the ejector slide with respect to the 75 member 58.

While the preferred form of the invention has been herein shown and described, it is to be understood that various changes may be made in the details of construction and in the combination and arrangement of the several parts, within the scope of the claims, without departing from the spirit of this invention. 80

What is claimed as new is:—

1. In a vending machine a delivery station, means for holding a supply of articles adjacent said station, an ejector for the articles, means for actuating the ejector, a container for holding an additional supply of articles, means pivotally mounting said container, means automatically rendered active at a predetermined time in the operation of the machine whereby the said container will be moved about its pivot by the operation of the ejector and whereby the articles in said container may be ejected by said ejector, and means for locking said container in either of the positions to which it is moved, the said locking means being rendered inactive in one position of the container by the third recited means. 85

2. In a vending machine, means for maintaining a supply of articles to be vended, a pivotally mounted container for holding an additional supply of articles, an ejector operable upon the articles in the first said supply to successively deliver them therefrom, positively actuated 100 means operating to shift the said container to a position that the articles therein will be successively delivered therefrom by said ejector when the articles in the first recited supply are exhausted, and means for locking said container against shifting movement, the first said means embodying means operating upon said locking means for rendering the same inactive when said container is in one of its positions. 105

3. A vending machine, means for holding a 110 supply of articles to be vended, a container fixed against bodily movement but pivotally mounted for swinging movement in the machine about a horizontal axis, an ejector for successively ejecting the articles from the first said supply, a 115 normally inactive pivotally mounted member for shifting the container about its pivot, a normally inactive catch means operating in the absence of articles in the first said supply for rendering said catch active to connect the said member with 120 said ejector for positively shifting thereby the said container upon a subsequent operation of the ejector, to position the articles therein to be ejected by the ejector in the absence of articles in the first said supply. 125

4. A vending machine, means for holding a

supply of articles to be vended, a container fixed against bodily movement but pivotally mounted for swinging movement in the machine, an ejector for successively ejecting the articles from 130 the first said supply, a normally inactive member, a normally inactive catch, means operating in the absence of articles in the first said supply for connecting the said member with said ejector for shifting the said container upon a subsequent operation of the ejector to position the articles therein to be ejected by the ejector, and means for locking the container in one of its 135 positions, the said member also acting upon the said locking means to render the same inactive. 140

5. In a vending machine, means for holding a plurality of supplies of articles to be vended, an ejector, one of said supplies being normally positioned that the articles therein will be successively delivered therefrom upon the opera- 145

150

- tion of the ejector, a container for the other of said supplies normally maintained against ejection of the articles therefrom by the ejector, said container being fixed against bodily movement but mounted for swinging movement about a horizontal pivot, and means responsive to the operation of the ejector in the absence of articles in the first said supply to positively swing the container about its pivot so that the articles therein will be successively delivered upon subsequent operation of the said ejector.
6. In a vending machine, means for holding a plurality of supplies of articles to be vended, an ejector, one of said supplies being normally positioned that the articles therein will be successively delivered therefrom upon the operation of the ejector, a container for the other of said supplies and normally maintained against ejection of the articles therefrom by the ejector, said container being fixed against bodily movement but mounted for swinging movement about a horizontal pivot, and means whereby the actuation of the ejector in the absence of articles in the first said supply will positively shift the said other supply into a position that upon subsequent operations of the ejector the articles will be successively delivered by the ejector from the said other supply.
7. In a vending machine, means for holding a plurality of supplies of articles to be vended, an ejector, one of said supplies being normally positioned that the articles therein will be successively delivered therefrom upon the operation of the ejector, a container for the other of said supplies being normally maintained against ejection of the articles therefrom by the ejector, said container being fixed against bodily movement but mounted for swinging movement, means whereby the actuation of the ejector in the absence of articles in the first said supply will positively swing the said container about its pivot into a position that upon subsequent operations of the ejector the articles will be successively delivered by the ejector from the said other supply, and locking means for maintaining the said other supply against shifting movement, the container shifting means operating upon said locking means for rendering the latter inactive when the container is in one of its positions.
8. In a vending machine, means for maintaining a supply of articles to be vended, an ejector, means for actuating the ejector to successively deliver said articles, a container for holding an additional supply of articles to be vended, said container being fixed against bodily movement but mounted for swinging movement, a normally inactive actuating member for swinging the said container about its pivot, a catch carried with the ejector, and means controlled by the articles in the first said supply for normally rendering said catch inactive, the said catch being rendered active in the absence of articles in the first said supply for connecting the ejector with the said member to operate the latter to swing said container about its pivot into a position that upon subsequent operations of the ejector the articles will be successively delivered by the ejector from the container.
9. In a vending machine, means for maintaining a supply of articles to be vended, an ejector, means for actuating the ejector to successively deliver said articles, a shiftable container for holding an additional supply of articles to be vended, a normally inactive actuating member for shifting the said container, a catch carried with the ejector, means controlled by the articles in the first said supply for normally rendering said catch inactive, the said catch being rendered active in the absence of articles in the first said supply for connecting the ejector with the said member to shift said container into a position that upon subsequent operations of the ejector the articles will be successively delivered by the ejector from the container, locking means for maintaining said container against shifting movement, and means whereby the said actuating member when connected with said ejector will render the said locking means inactive.
10. In a vending machine, means for maintaining a plurality of separate supplies of articles to be vended, an ejector for successively ejecting the articles from one of said supplies, a container for the other of said supplies, said container fixed against bodily movement but mounted for swinging movement about a horizontal pivot, and means responsive to the operation of said ejector and controlled by the absence of articles in the first recited supply for causing the ejector to swing the container about its pivot into a position that the articles therefrom will be successively ejected by the ejector upon the subsequent operation of the ejector.
11. A vending machine comprising a stationary container and a swinging container for the articles, an ejector for successively ejecting the articles from the stationary container in advance of the articles from the swinging container, normally inactive means for moving the swinging container into a position that the ejector will successively eject the articles therefrom when the stationary container is empty, and means operating automatically to connect the said normally inactive means with the ejector to move the swinging container, the last recited means being normally maintained inactive by the presence of articles in the stationary container.
12. In a vending machine a stationary container and a swinging container for the articles, each having a discharge outlet, a reciprocating ejector for successively vending the articles from the stationary container, a pivotally mounted member adapted to engage and move the swinging container about its pivot to position the outlet thereof that the ejector will successively vend the articles therefrom, and means rendered active by the absence of articles in the stationary container for automatically connecting the said pivot member with the ejector to be moved thereby to shift the swinging container to have the articles vended therefrom, the last said means being normally maintained inactive by the presence of articles in the stationary container.

MYRON H. RICHARDSON. 145
